AUTOMATIC VOLUME CONTROL CIRCUIT

Loy E. Barton, Collingswood, N. J., assignor to
Radio Corporation of America, a corporation
of Delaware

Application December 16, 1933, Serial No. 702,714

10 Claims. (Cl. 250—20)

My present invention relates to amplifier control arrangements, and more particularly to a novel and improved arrangement for automatic volume control of a radio receiver.

5 It is one of the main objects of my present invention to provide an automatic volume control system for a radio receiver wherein there is provided a normal bias for the controlled tubes which is greater than normal for the said tubes, the 10 system utilizing a network of resistors in the grid return for the controlled tubes so that the high bias on the controlled tubes is bucked down to a normal value, the bucking current leaving the 15 automatic volume control diode plate at a positive potential with respect to the cathodes of the controlled tubes.

Another important object of this invention is to provide an automatic volume control arrangement for a radio receiver so arranged that the 20 output electrode for the automatic volume control will be positive with respect to the cathodes of the controlled tubes under normal conditions, the volume control arrangement being additionally so constructed that the tendency of the system 25 to flutter is reduced.

Another important object of the present invention is to provide an automatic volume control system for a radio receiver, wherein a diode is utilized as an automatic volume control element, 30 and the diode anode, which delays the automatic volume control action, is normally positive with respect to the cathodes of the controlled tubes until the automatic volume control action is initiated.

Still other objects of the invention are to improve generally the simplicity and efficiency of automatic volume control arrangements, and to especially provide a superheterodyne receiver 35 which embodies the improved type of automatic volume control arrangement in a compact and highly economical manner from the manufacturing viewpoint.

The novel features which I believe to be characteristic of my invention are set forth in particular in the appended claims. The invention itself, however, both as to its organization and method of operation, will best be understood by reference to the following description taken in connection with the drawing in which I have 40 indicated diagrammatically a circuit organization whereby my invention may be carried into effect.

In the accompanying drawing there is shown a 45 superheterodyne receiver of conventional form, and this receiver embodies the usual signal col-

lector device A which may be the conventional grounded antenna circuit, a radio frequency signal distribution line, or a loop antenna. The collected signals are fed into a radio frequency amplifier 1, and the amplified radio frequency signals are then impressed upon a frequency changer network 2. The networks 1 and 2 may be given any form well known to those skilled in the art. For example, the network 1 may be a tunable radio frequency amplifier, and the network 2 5 may embody separate first detector and local oscillator tubes. Alternately, the network 2 may be a composite first detector-local oscillator network of the type disclosed by Haines in his application Serial No. 663,171, filed March 28th, 1933, 10 and in that case a gain control bias can be applied to the signal grid of the composite first detector-local oscillator.

The tuning means of the signal circuits and local oscillation circuits of the networks 1 and 2 20 are not shown, but those skilled in the art are well aware of the construction and know that there is fed into the tuned circuit 2' energy of a substantially constant intermediate frequency. The intermediate frequency energy is then amplified in an intermediate frequency amplifier which embodies a tube 3, and the latter is shown as of the 25 58 or pentode type. The tuned input circuit 4 of the amplifier tube 3 is coupled to the circuit 2', and the transformer 5, having a tuned primary 30 and a tuned secondary, couples the anode circuit of the amplifier tube 3 to the diode second detector circuit.

The numeral 55 designates an electron discharge tube known as a duplex diode triode tube, 35 also known as a 55 type tube, and comprises within a common tube envelope a triode section and a pair of diode sections. These sections use a common cathode, and the specific construction of the tube has been described and claimed by T. M. 40 Shrader in his application Serial No. 622,140, filed July 12th, 1932.

The diode anode 6 is connected to the cathode lead of tube 55 through a path which includes the 45 tuned input circuit 5' and the resistor 21 connected in series, the resistor 21 being shunted by radio frequency by-pass condenser 7' and the volume control comprising resistor network 7 and audio by-pass condenser 21'. The control grid of the triode section of tube 55 is connected to the 50 arm 9 of the volume control potentiometer 7 through a resistor 8. The audio frequency by-pass condenser 21' connects the cathode side of potentiometer 7 to the cathode of the tube 55. The amplitude of the audio frequency component 55

of the detected signal energy impressed upon the grid of tube 55 is controlled by the position of arm 9; however, it will be noted that the bias for the triode section of tube 55 is unchanged by the 5 position of arm 9.

The remaining diode anode 10 functions as the automatic volume control element, and is connected to the positive side of the direct current power supply source through a path which includes lead 11 and resistor R₃. The cathode of tube 55 is connected to the negative side of the direct current power supply source through a path which includes lead 12 and resistor R₅ in series. The direct current power supply source is of a 15 conventional type too well known to those skilled in the art to require any further description. Between the positive and negative terminals of the source there is connected a path which includes the iron core choke coil 13 and resistor R₆ in series, the junction point of coil 13 and the resistor being grounded. The coil 13 is preferably the field coil of the loud speaker.

The plate of tube 55 is connected to the positive terminal of the direct current power supply source through a path which includes resistor 14 and lead 15, a radio frequency by-pass condenser 16 being connected between the cathode and one side of resistor 14. An audio and radio frequency by-pass condenser 17 is connected between the 30 cathode side of condenser 16 and ground. Condenser 18 is employed to transmit the audio frequency signal energy in the plate circuit of tube 55 to the succeeding audio frequency amplifier; the latter may be a power tube if desired, and the 35 amplified audio signal energy may then be reproduced by the loud speaker.

The automatic volume control path embodies the lead 11, the resistor R₂, and the lead 20 which is connected to the grid circuits of the controlled 40 tubes. This path has been labelled "AVC" to clearly point out that this is the automatic volume control path. A resistor R₁, in the case of the intermediate frequency amplifier tube 3, is connected between the lead 20 and ground, and the 45 usual direct current blocking condenser 21 is connected between the cathode of tube 3 and the signal grid thereof. In the cathode circuit of tube 3 there is arranged a resistor having one side thereof grounded, the ground side of the resistor being connected to an adjustable tap 22 which is 50 utilized to vary the magnitude ratios between the portions R₄ and R₇ of the resistor.

The type of automatic volume control arrangement shown in the aforescribed circuit is described and claimed in my co-pending application 55 Serial No. 640,946, filed November 3rd, 1932. One of the essential features of this type of automatic volume control arrangement is that no signal energy is directly impressed on the automatic volume control diode anode 10. Essentially, the 60 automatic volume control action does not commence until the diode anode 10 is at least at cathode potential, and begins to perform its function when it becomes positive with respect to the cathode.

In other words, the diode which includes the anode 10 functions as a delay device for the automatic volume control action until the intensity 65 of signals impressed upon circuit 5' has assumed a value sufficient to bring the potential of the cathode of tube 55 negative with respect to the diode anode 10. Normally, that is with no signals impressed upon the network 5', the potential 70 of the cathode of tube 55 is positive with respect

to the diode anode 10. As signals of proper intensity are impressed upon circuit 5' the grid of tube 55 becomes increasingly negative, and the flow of current through the space current path of the triode section of tube 55 decreases. This 5 results in bringing the cathode potential negative with respect to the diode anode 10.

However, with no signal input to the receiver the diode anode 10 is positive with respect to the potential of the cathode of amplifier tube 3. In 10 the present application the potential relations between the diode anode 10 and the cathode of tube 3 will be discussed in detail, but it is to be clearly understood that the same explanation is to be considered as applicable to the circuits of 15 networks 1 and 2, the latter not being shown in detail in order to simplify the present description. As soon as signals of the proper intensity are impressed upon the second detector circuit the potential of diode anode 10 may become negative 20 with respect to the cathodes of the controlled tubes. With no signals impressed upon the circuit 4 there is developed an abnormally high self-bias on the grid of tube 3. This is accomplished by properly choosing the values of the self-bias- 25 ing resistor R₇.

In order that the tubes 1, 2 and 3 may have normal bias a current is caused to flow from the positive terminal of the plate supply through resistors R₃, R₂ and R₁ so that there is sufficient 30 positive potential across resistor R₁ with negative potential at ground to reduce the abnormally high bias on the controlled tubes to normal values. Since the current through resistor R₁ also passes through R₂ there is a drop in this resistor greater 35 than the normal bias of tubes 1, 2 and 3. Therefore, the anode 10 is normally at a positive potential with respect to the cathodes of the tubes 1, 2 and 3, the amplitude of which is a function of the relative values of resistors R₁, R₂ and R₃. 40 The following example will indicate practical operating voltages and resistor values when the potential value of the positive terminal of the power supply with respect to ground is about 254 volts. It will be noted that as the signal to the 45 second detector increases so that automatic volume control voltage is applied to the radio frequency and intermediate frequency tubes, the potential of the cathodes of these tubes with respect to ground changes. This varying of potential further delays the action of the automatic 50 volume control, and may be used for such functions as automatic selectivity control in cases where a potential opposite to the automatic volume control potential is desired.

Potential of cathode of tube 3 to ground=23 55 volts

Drop across R₁ at no signal=20 volts

Therefore: normal bias for tube 3=3 volts

R₁ may be one megohm and R₂=20,000 ohms 60 then

R₃=approximately 12 megohms, and anode 10 will be about one volt positive with respect to the cathode of tube 3.

It will, therefore, be seen that there has been 65 provided by the present invention an automatic volume control arrangement for a radio receiver wherein the automatic volume control action is delayed until the signal intensity attains a desired value, this being accomplished by normally 70 maintaining the volume control diode anode negative with respect to the cathode of tube 55. Furthermore, by the network of resistors described heretofore, and which network is used in conjunction with the automatic volume con- 75

5 trol resistor in the grid returns for the control tubes, it is possible to maintain the automatic 10 volume control anode 10 normally at a positive potential, that is in the no signal condition, with respect to the cathodes of the controlled tubes. This is generally accomplished by bucking down the abnormally high bias on the controlled tubes to a normal value, the bucking current leaving the diode anode 10 at a positive potential with 15 respect to the cathodes of the controlled tubes.

10 While I have indicated and described a system for carrying my invention into effect, it will be apparent to one skilled in the art that my invention is by no means limited to the particular organization shown and described, but that many modifications may be made without departing from the scope of my invention, as set forth in the appended claims.

15 What I claim is:—

20 1. An automatic volume control arrangement for a radio receiver which embodies a high frequency amplifier, a detector device coupled to the output of said amplifier, an electron discharge device having its grid connected to a point of 25 audio frequency potential in the circuit of the detector, an anode disposed adjacent the cathode of the said electron discharge device, means for maintaining the cathode of the electron discharge device at a positive potential with respect to the 30 said anode when no signals are impressed upon the detector, a direct current connection between the said anode and the grid circuit of said amplifier, and resistive means electrically associated with the said anode to maintain the anode at a 35 positive potential with respect to the cathode of the amplifier in the said no signal condition.

25 2. An automatic volume control arrangement for a radio receiver which embodies a high frequency amplifier, a detector device coupled to the 40 output of said amplifier, an electron discharge device having its grid connected to a point of audio frequency potential in the circuit of the detector, an anode disposed adjacent the cathode of the said electron discharge device, means for 45 maintaining the cathode of the electron discharge device at a positive potential with respect to the said anode when no signals are impressed upon the detector, a direct current connection between the said anode and the grid circuit of said 50 amplifier, and resistive means electrically associated with the said anode to maintain the anode at a positive potential with respect to the cathode of the amplifier in the said no signal condition, said 55 detector device comprising an anode disposed adjacent said cathode, and both said devices and said first anode being included in a common tube envelope.

30 3. An automatic volume control arrangement for a radio receiver which embodies a high frequency amplifier, a detector device coupled to the output of said amplifier, an electron discharge device having its grid connected to a point of audio frequency potential in the circuit of the detector, an anode disposed adjacent the cathode 55 of the said electron discharge device, means for maintaining the cathode of the electron discharge device at a positive potential with respect to the said anode when no signals are impressed upon the detector, a direct current connection between the 60 said anode and the grid circuit of said amplifier, and resistive means electrically associated with the said anode to maintain the anode at a positive potential with respect to the cathode of the amplifier in the said no signal condition, said 65 resistive means being connected between the space

current path of the electron discharge device and the said grid circuit and being included in said direct current connection.

4. An automatic volume control arrangement 5 for a radio receiver which embodies a high frequency amplifier, a detector device coupled to the output of said amplifier, an electron discharge device having its grid connected to a point of audio frequency potential in the circuit of the detector, an anode disposed adjacent the cathode 10 of the said electron discharge device, means for maintaining the cathode of the electron discharge device at a positive potential with respect to the said anode when no signals are impressed upon the detector, a direct current connection between the said anode and the grid circuit of said 15 amplifier, and resistive means electrically associated with the said anode to maintain the anode at a positive potential with respect to the cathode of the amplifier in the said no signal condition, 20 said electron discharge device comprising an amplifier of the audio voltage developed by the detector, and the cathode of said electron discharge device becoming negative with respect to the said anode when signals are impressed on 25 said detector.

5. In combination in a radio receiver, a high frequency amplifier provided with a resistor in its space current path, the resistor being of a value sufficient to provide a grid bias for the 30 amplifier which is abnormally high, a rectifier coupled to the amplifier output, a device of asymmetric conductivity including an anode electrically associated with said rectifier, means operatively associated with the said device and resistor for reducing said high bias to a desired 35 normal value and for maintaining said anode positive with respect to the amplifier cathode, and a direct current connection between said anode and the grid circuit of said amplifier. 40

6. In combination in a radio receiver, a signal transmission tube provided with a resistor in its space current path, the resistor being of a value sufficient to provide a signal grid bias for the tube which is abnormally high, a signal rectifier 45 coupled to the tube output, a device of asymmetric conductivity operatively associated with said rectifier, and arranged to be conductive when signals above a predetermined amplitude are rectified, a direct current connection between a cold 50 electrode of said device and the grid circuit of said tube, a source of direct current voltage, a resistive network connected to said source, connections from the grid circuit of said tube and said resistor to said network such that said 55 high bias is reduced to a desired operating value, and a connection from said cold electrode to a point on the resistive network such that the cold electrode is positive with respect to the cathode of said tube for signals less than said predetermined amplitude. 60

7. In combination in a radio receiver, a multiple duty tube comprising a pair of diode sections and a triode section, one of said diode sections being arranged to have signal energy impressed 65 upon it and including a resistor in its circuit for developing a direct current potential component from the signal energy, the grid of said triode section being connected to a point of negative potential on the resistor, a high frequency amplifier whose gain is to be controlled, a direct current connection between the grid circuit of said controlled amplifier and the anode of the second diode section, means in the space current path 70 of the said triode section for maintaining the 75

- common cathode of said multiple duty tube at a positive potential with respect to the anode of the second diode section when no signals are received, and means electrically associated with the controlled amplifier for maintaining the grid of the amplifier at an abnormally high bias with respect to the cathode thereof.
8. In combination in a radio receiver, a multiple duty tube comprising a pair of diode sections and an amplifier section, one of said diode sections being arranged to have signal energy impressed upon it and including a resistor in its circuit for developing a direct current potential component from the signal energy, the grid of said amplifier section being connected to a point of negative potential on the resistor, a high frequency amplifier whose gain is to be controlled, a direct current connection between the grid circuit of said controlled amplifier and the anode of the second diode section, means in the space current path of said amplifier section for maintaining the common cathode of said multiple duty tube at a positive potential with respect to the anode of the second diode section when no signals are received, means electrically associated with the controlled amplifier for maintaining the grid of the amplifier at an abnormally high bias with respect to the cathode thereof, and a plurality of resistors electrically associated with said direct current connection and the common cathode of the multiple duty tube for reducing said high bias to a normal value and for maintaining the second

anode at a positive potential with respect to the cathode of the controlled amplifier.

9. In a signaling system, a signal transmission tube having a cathode and control grid, a diode, means for maintaining the diode anode normally positive with respect to said transmission tube cathode, means for maintaining the control grid of the transmission tube normally at a desired operating negative bias with respect to the said cathode, means for causing said diode anode to become negative with respect to said cathode when signals are transmitted by said tube, and a direct current connection between said control grid and diode anode whereby the transmission efficiency of said tube is automatically regulated. 15

10. In a signaling system, a signal transmission tube having a cathode and control grid, a diode, means for maintaining the diode anode normally positive with respect to said transmission tube cathode, means for maintaining the control grid of the transmission tube normally at a desired operating negative bias with respect to the said cathode, means for causing said diode anode to become negative with respect to said cathode when signals are transmitted by said tube, said last means normally causing the diode cathode to be positive with respect to the anode thereof, in the absence of signals, and a direct current connection between said control grid and diode anode whereby the transmission efficiency 30 of said tube is automatically regulated.

LOY E. BARTON.
